UNITED STATES PATENT OFFICE

CHARLES L. PEIRCE, JR., OF PITTSBURGH, PENNSYLVANIA

METAL PLATING

Original application filed May 27, 1922, Serial No. 564,273. Divided and this application filed June 27, 1925. Serial No. 39,979.

This invention relates to a new and improved apparatus for metal coating for such articles as bolts, rods, screws, hangers, brackets, etc., and is a division of my previously filed application Serial No. 564,273, filed May 27, 1922.

An object of the invention is to produce a new and improved apparatus for metal coating which may be employed in connection with galvanizing and similar processes where it is important to minimize the expense of the metal coating operation.

A further object is to produce an improved apparatus for metal coating so constructed and arranged as to insure a complete and uniform coating on each coated article and which, at the same time, avoids waste of the coating material.

A further object is to produce an apparatus for metal coating which is simple and cheap to manufacture and assemble, rugged in construction and rapid in operation.

These and other objects are attained by means of this invention, one embodiment of which is illustrated in the drawings accompanying and forming a part hereof, in which Figure 1 is a diagrammatic view illustrating an apparatus constructed in accordance with one form of this invention.

Fig. 2 is an enlarged view of a support rack shown in connection with associated apparatus.

Fig. 3 is a plan view of the rack shown in Fig. 2.

Fig. 4 is a side elevation of the rack shown in connection with means for simultaneously raising it off a rotating element and decreasing its speed of rotation.

Articles to be galvanized are ordinarily submerged in a bath of molten galvanizing metal and are allowed to remain in the bath until the coating metal adheres thereto by alloying with the surface metal thereof. The article is then removed from the bath and some effort is made to dislodge excess coating metal therefrom. After the excess metal has been removed, the article is immersed in water or otherwise cooled.

Various forms of apparatus have been employed for galvanizing and removing excess

coating material from the coated articles, but so far as I know, none of the machines now in use is entirely satisfactory, since they do not give uniform results in connection with relatively large articles such as screws, bolts, 55 hooks, hangers, brackets and the like.

One of the features of my invention is that a number of separate articles may be simultaneously coated and then simultaneously subjected to centrifugal action in such a way that the excess metal on all parts of each article is subjected to substantially the same dislodging force with the result that each article is coated with a thin and uniform covering of the coating metal. Another feature of my invention is that the articles are almost immediately accelerated to the desired rotational speed after they are removed from the bath of molten metal and consequently are quickly subjected to sufficient centrifugal force to dislodge the excess coating material before it has cooled sufficiently to resist the dislodging force.

In carrying out my invention, I employ a frame or rack 6 which is provided with separate means, such as apertures or a recess for holding each article to be coated in a fixed position with relation to the axis of the rack. The separate articles are preferably so mounted on the frame that their major axes extend substantially parallel to the axis of the frame. The frame, with the articles in place on it, is then immersed in a bath of molten metal shown diagrammatically at 5 in Fig. 1. After the articles have remained in the bath a sufficient period to insure proper coating, the rack, with the articles in place on it, is removed from the bath and is moved into clutching engagement with a continuously rotating spindle in such a way that it is almost instantaneously accelerated to the speed of the rotating spindle and is caused to rotate about its axis at a speed sufficient to dislodge the excess coating material from each article on the rack.

While the articles are subjected to this whirling action of the spindle, they are retained in fixed relation to the axis of rotation of the rack and are so located on the rack that the dislodging force occasioned by the rotation is substan- 100

tially the same for each article and is substantially uniform throughout the entire length of each article. With this arrangement, a uniform coating of all the articles is obtained and the coating on each article is substantially uniform over the entire article.

As shown in the drawings, the rack 6 for the articles to be coated consists of two spaced plates 7, each provided with a number of article-receiving apertures 8 arranged symmetrically around the axis of the rack. The plates are located one above the other and each aperture 8 in the upper plate is aligned with a similar aperture in the lower plate. The plates are secured to and are spaced by a hanger 9 which is bent to form a loop 10 adapted to be engaged by a supporting hook.

13. The hook 13 is preferably a ball-bearing swivel hook, as shown, or is otherwise so constructed that the rack may turn freely while supported by it. Any suitable means may be employed for lifting and moving the rack but, as illustrated in Fig. 1, I employ a trolley 14 operating on a track 15 and a tackle 16 secured to the trolley for raising and lowering the rack.

The articles to be coated are located in the recesses around the axis of the rack as shown in Figs. 1, 2 and 4. The rack is then engaged by the hook 13 and is moved to position over a bath of molten metal. The tackle 16 and the trolley 14 may be employed in so moving the rack and the tackle may be employed in lowering the rack into the bath of metal. After the articles to be coated have been subjected to the bath, the rack is again lifted so that the articles clear the surface of the bath and the rack is moved by means of the trolley and the supporting tackle to position above a continually rotating spindle 17. As shown in Fig. 1, the spindle is located in a convenient position between the bath 5 and a tank 18 adapted to contain water. The spindle stands vertically and is provided at its upper end with a cone 19 which is rigidly secured thereto and is adapted to engage the rack. For this purpose the two plates of the rack are provided with axially aligned apertures of such relative diameters that their edges will simultaneously engage the cone 19 as the rack is moved downwardly over it.

The engagement of the cone 19 with the rack operatively couples the rack to the spindle 17 and consequently causes the rack to revolve with the spindle. In addition to this, the cone performs to some extent the function of one element of a friction clutch, whereas the contacting edges of the rack perform the function of the co-operating element of such a clutch with the result that the rack is quickly accelerated to the speed of the spindle. The rotation of the rack and the articles carried by it dislodges the excess molten metal from the articles. In order to prevent this hot metal being thrown about,

I employ a safety shield 21 which may be lowered from a point above so that it surrounds the rack while it is being rotated on the spindle. As shown, the shield may be supported by means of ropes and pulleys 70 from the trolley 15.

In the apparatus illustrated, the spindle is driven by a motor 22 through the agency of beveled gears 23. The spindle is mounted in a stationary form 24 and is preferably provided with a weighted wheel such as a fly wheel 25 for the purpose of absorbing the shock when the rack is mounted on or removed from the cone 19. As shown in Fig. 1, the frame is provided with a stationary table 26, on which the protective screen may rest during the whirling of the rack.

In Fig. 4 I have shown means, in addition to the hook 13 for lifting the rack out of operative engagement with the cone 19. As illustrated, a lever 27 is fulcrumed on the stationary pivot and is bifurcated at one end for the purpose of straddling the cone. The forks of the bifurcated end are pivotally secured to a ring 28 which is adapted to be moved upwardly by the lever so that its upper edge engages and lifts the rack 6 from the cone. It will be apparent that the engagement of the ring with the rack will impart a braking action to the rack and will therefore, tend to stop the rotating motion of the rack as soon as the rack moves out of engagement with the cone.

After the excess metal has been removed from the coated articles carried by the rack, the rack with the articles in place on it is dropped into the bath 18 of the cooling water. The hook 13 and its associated supporting device may be employed in moving the rack from the spindle 17 and into the bath 18. Where the brake 28 is not employed the support and the articles are plunged into a bath of cooling liquid for the purpose of checking the rotation and cooling the articles.

While I have described and illustrated but one embodiment of my invention, it will be apparent that various changes, additions, omissions and substitutions may be made in the apparatus illustrated without departing 115 from the spirit and scope of the invention set forth by the appended claims.

What I claim as my invention is:

1. In an apparatus for coating articles, a rotary spindle having circular engaging faces, a frame for securely holding a plurality of articles to be coated and adapted to be rotated by said spindle, an overhead structure including a swivel for holding said frame and moving it from a coating bath 120 into engagement with said circular faces of said spindle so as to subject the coated articles to centrifugal force for dislodging excess coating material and a shield adapted to surround said frame and supported for 125

vertical movement from said overhead structure.

2. In an apparatus for coating articles, a rotary spindle, a frame for securely holding a plurality of articles to be coated and adapted to be rotated by engagement with said spindle, and means for raising said frame away from said spindle and stopping the rotation of said frame.

10 3. In an apparatus for coating articles, a rotary spindle, a frame for securely holding a plurality of articles to be coated and adapted to be rotated by engagement with said spindle, a ring movably mounted adjacent said spindle and means for moving said ring into engagement with said frame so as to lift the same away from said spindle and stop the rotation of said frame.

20 4. In an apparatus for coating articles, a rotary spindle, having a tapered end forming a conical clutch face, a frame for securely holding articles to be coated and having perforations adapted to receive and frictionally engage the conical face of said spindle.

25 In testimony whereof, I have hereunto subscribed my name this 26th day of June, 1925.
